UNITED STATES PATENT OFFICE.

LESTER E. BUDD, OF PHILADELPHIA, PENNSYLVANIA.

GRATE STRUCTURE.

Application filed March 6, 1925. Serial No. 13,433.

My invention relates to grate structures for boilers and its object is to provide a grate structure of simple construction, which may be operated by hand or power to evenly shift the coal bed from the feed to the ash end of the grate surface.

This object, and other advantageous ends which will be described hereinafter, I attain in the following manner, reference being had to the accompanying drawings in which—

Figure 1 is a fragmentary central section through a furnace having my grate structure applied thereto,

Figure 2 an enlarged view of the grate structure shown in Figure 1, illustrating the grate sections in another position,

Figure 3 a view similar to Figure 2 showing the parts in another position,

Figure 4 a fragmentary enlarged bottom plan view of the grate structure shown in Figure 1,

Figures 5 and 6 bottom plan views of grate sections made in accordance with my invention,

Figure 7 a fragmentary front view of the furnace shown in Figure 1 illustrating the operating mechanism,

Figure 8 a side view of the operating mechanism shown in Figure 7,

Figure 9 a plan view of the mechanism shown in Figure 7,

Figure 10 an enlarged central section through a grate bar unit which forms a part of my invention, and

Figure 11 a reduced fragmentary section on line 11—11 of Figure 1.

Referring to the drawings, 1 indicates a frame and 2 a series of grate bar units pivotally mounted on the frame and arranged to form an inclined grate surface. Each unit consists of a grate section 3 mounted on a pivot rod 4 and adapted to swing in one direction, and a grate section 5 mounted upon the same pivot rod but adapted to swing in reverse direction.

Normally, the upper faces of grate sections 3 and 5 are flush with each other, but section 3 is adapted to be swung both below and above the plane of the grate surface and section 5 is adapted to be swung downwardly from and upwardly to but not above that plane. The grate sections extend the width of the grate and section 3 is provided with hubs 7 by which it is supported on the pivot rod. Section 3 is provided with perforations 6 and section 5 with perforations 10,

Section 3 is provided, on its face side with an arcuate guard plate 8 adapted to prevent coal from falling into the ash pit when that section is swung above the plane of the grate surface. The free side of section 5 may be formed with a series of spaced projections 11 which provide additional air spaces, and its other side is provided with hooks 12 which take over rod 4 and fit between the hubs of section 3. An arcuate part 13 between hooks 12 prevents coal from falling between section 3 and the pivot rod when the sections are swung downwardly. Hubs 7 and hooks 12 serve to hinge the respective sections upon the pivot rods. One of the hubs of section 3 has a depending arm 9 by which the section may be actuated, and an arm 14 depends from section 5 by which that section may be actuated. The actuating arms are designed to be moved concurrently but arm 9 is so disposed that movement in one direction will move section 3 downwardly from its flush position and movement in the other direction will move it upwardly to and beyond its flush position, and arm 14 is so disposed that movement in one direction will move section 5 downwardly and movement in the other direction will move it upwardly to but not beyond its flush position.

The downward movement of the grate sections permits the coal to fall forward into the angles between the sections. Upward movement first lifts the coal out of the angles and restores the sections to their flush position. Continued upward movement of section 3 pushes the coal resting upon that section onto section 5. The downward movement of the succeeding unit allows the coal on section 5 to fall into another angle from which it is lifted and forced onto the succeeding section 5. The coal bed is thus gradually shifted from the front to the rear of the inclined grate without permitting any material part of the unconsumed fuel to get to the ash pit.

Movement may be imparted to the grate sections by any suitable mechanism. The simple operating mechanism shown is designed for manual operation but may be easily modified for power operation. It consists of a rock shaft 17 having its bearings in a bracket 18 in front of the furnace and having three arms, 15, 16 and 24. Arm 24 is adapted to be engaged by a socket 25 in a handle 23. Arm 15 is pivotally con-

nected with a link 19 which is pivotally connected with a tie bar 20 which is connected with arms 9 which depend from hubs 7 on grate sections 3. Arm 16 is in like manner 5 connected with arms 14, depending from grate sections 5, through a link 21 and a tie bar 22. Rock shaft 17 and arms 15, 16 and 24 constitute a rock lever and, by means of the connections above described serve to impose 10 concurrent movement to the grate sections 3 and 5 for shifting the coal bed.

Inasmuch as the grate sections are supported on one side only, their weight and the weight of the coal will tend to swing the 15 sections downwardly. To overcome this tendency, counterbalancing means may be connected with rock shaft 17. As such means, I have shown a spiral spring 26 having one end fixed to bracket 18 and the 20 other end to a collar 27 carried by rock shaft 17. The tension of the spring should be sufficient to normally counter-balance the downward pressure exerted by the grate sections and the coal thereon. This permits 25 the grate sections to be actuated by pressure sufficient to overcome the friction, and the friction will normally hold the grate sections in whatever positions they may be when actuation of the lever stops, though it is desirable 30 to also provide positive means for locking the sections in their flush position. For this purpose, I preferably provide a pair of ledges 28 on an extension 29 of bracket 18 to prevent the handle from being 35 lifted off lug 24 until an ear 30 on the handle socket is in registry with the space 31 between the ledges. When the handle is in this position it may be lifted off and lug 24 locked in position by swinging a bifurcated 40 locking member 32, on extension 29, to partially embrace lug 24.

In case a section 5 should burn out or become warped or defective in any manner, it may be removed by merely unhooking hooks 45 12 from pivot rod 4, and replaced by a new bar.

It will be seen that with the grate structure above described, the coal bed may be easily and uniformly shifted along the grate 50 surface.

While I have described my invention as taking a particular form, it will be understood that the various parts may be changed without departing from the spirit thereof, 55 and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. In a grate structure, a transverse grate unit consisting of a pivot rod, a grate section hinged thereto and adapted to be swung

to positions below and above the plane of the grate surface, a grate section hinged to the rod and adapted to swing below the plane of the grate surface only, and means for actuating the sections. 70

2. In an inclined grate structure, a series of transverse grate units, each consisting of a pivot rod, a grate section hinged thereto and adapted to be swung to positions below and above the plane of the grate surface, a grate section hinged to the rod and adapted to be swung to positions below the plane of the grate surface only, and means for actuating the sections. 75

3. In an inclined grate structure, a series of transverse grate units, each consisting of a pivot rod, grate sections hinged thereto and adapted to swing, the upper faces of the sections being normally flush with each other, one section adapted to be swung to positions below and above the plane of the grate surface and the other section to be swung to a position below the plane of the grate surface only, and means for actuating the sections. 80 85

4. In an inclined grate structure, a series of transverse grate units, each consisting of a pivot rod, grate sections hinged thereto and adapted to swing, the upper faces of the sections being normally flush with each other, one section adapted to be swung to positions below and above the plane of the grate surface and the other section to be swung to a position below the plane of the grate surface only, means for counterbalancing the pressure of the coal and the grate sections, and means for actuating the sections. 90 95 100

5. In an inclined grate structure, a series of transverse grate units, each consisting of a pivot rod, grate sections hinged thereto and adapted to swing, the upper faces of the sections being normally flush with each other, one section adapted to be swung to positions below and above the plane of the grate surface and the other section to be swung to a position below the plane of the grate surface only, means for counterbalancing the pressure of the coal and the grate sections, means for actuating the sections, and means for locking them in their normal positions. 105 110 115

6. In a grate structure, a transverse grate unit consisting of a pivot rod, a grate section hinged thereto and adapted to be swung to positions below and above the plane of the grate surface and having an arcuate guard plate adapted, when the plate is swung above the plane of the grate, to prevent fuel from dropping into the ash pit, the other section being adapted to be swung below the plane of the grate surface only, and means for actuating the sections. 120

7. A transverse grate unit consisting of a pivot rod, a grate section having a hub pivot-

ed on the rod, the section being adapted to be swung below and above the plane of the grate surface, a grate section having hooks taking over the rods, the section being adapted to be swung below the plane of the grate surface only, and means for swinging the sections.

8. A grate structure including a frame, a series of pivot rods mounted therein; a series 10 of grate sections mounted upon the rods and adapted to swing to positions below and above the plane of the grate; a series of grate

sections mounted upon the rods opposite the sections of the first series respectively and adapted to swing to positions below the 15 plane of the grate, an arm depending from each section; a tie bar connecting the arms of each series of sections, and a rock shaft, having an arm connected with each tie bar, whereby the respective series of grate sections may be actuated.

In testimony whereof I have signed my name to this specification.

LESTER E. BUDD.
